UNITED STATES PATENT OFFICE.

JOHN J. BRANAGAN, OF MCKEES ROCKS, PENNSYLVANIA.

RAIL-CLAMP.

1,373,592.

Specification of Letters Patent.

Patented Apr. 5, 1921.

Application filed December 8, 1920. Serial No. 429,108.

To all whom it may concern:

Be it known that I, JOHN J. BRANAGAN, a citizen of the United States, residing at McKees Rocks, in the county of Allegheny and State of Pennsylvania, have invented 5 certain new and useful Improvements in Rail-Clamps, of which the following is a specification.

My invention relates to an improvement 10 in means for securing railroad rails to cross ties of the type shown in my prior United States Patents No. 1,256,199 of February 12, 1918, and No. 1,307,110 of January 17, 1919.

In my prior patents above enumerated, 15 metal cross ties are shown having chairs at each end thereof, each chair being provided with a locking flange adapted to engage the outside base flange of the rail. Between the end chairs are abutments, and clamps 20 engaging the side and the inner part of the base flange of the rail are held in clamped position by means of removable tapered wedge plates. Unless means are provided for positively locking the wedge plates in 25 position, especially on curves, they are liable to work loose and allow the clamp to become dislodged.

My present invention has for its object to 30 provide a locking means for the wedge plates, by means of which the plate may be held from accidental removal, and which shall be adjustable to correspond to the different positions to which the plates may be forced during the setting of the rails.

35 In the accompanying drawings which show several embodiments of my invention,—

Figure 1 is a perspective view of a curved rail and one end of a tie to which the rail is 40 secured by the means described, the wedge plate being provided with means for holding it in place;

Fig. 2 is a transverse section through a tie along the center of one of the wedge plates, 45 showing the means for holding the wedge plate from accidental removal;

Fig. 3 is a perspective view of the holding device;

Fig. 4 is a section through the clamping member and tie;

Fig. 5 is a perspective view of the clamping member used for engaging the rail;

Fig. 6 is a perspective view of a clamping plate adapted to be spiked to a wooden 55 tie;

Fig. 7 is a section corresponding to Fig. 2,

but showing a modification of the invention;

Fig. 8 is a perspective view of the wedge plate used in this modification; and 60

Fig. 9 is a perspective view of the fastener used in this modification.

In the drawings, 5 is across tie, in the form of a metallic I-beam, but any suitable form of tie might be used. A rail 6 of usual 65 form is secured to the tie by means of a chair having a laterally slotted vertically extending portion 7 adjacent the end of the tie (see Fig. 1) and adapted to engage the base flange and side of the rail. A slotted 70 abutment 8 is provided on the tie and is spaced a considerable distance from the portion 7. A slotted clamping member 9 is placed against the inside of the rail between the rail and abutment 8, its rail 75 engaging face having a groove therein in which the base flange of the rail fits so that the top and the bottom of the flange are engaged by the clamp. A gradually tapering wedge plate 10 having lateral fins 80 thereon for cooperative engagement with the grooves in the abutment 8 and clamping member 9 is driven between the clamping member and the abutment, and serves to hold the clamp in position. This construc- 85 tion is shown in my United States Patent No. 1,256,199. In order to prevent the clamp 9 from tending to twist sidewise when the wedge is driven in, I provide depending flanges 9' on the clamping member to engage 90 the edges of the tie which insure against such displacement. The construction of the clamping member is clearly shown in Fig. 5.

When a tie in the form of an I-beam is 95 used, one or more strengthening webs 5' may be formed therein directly under the rail to enable the tie to safely support the enormous loads to which they are subjected. The ties are also preferably a little wider at the bottoms than at the tops to give them 100 greater stability.

Instead of forming the clamping means on a metallic tie, they may be formed on a plate 7', as shown in Fig. 6, and this plate may be spiked or otherwise secured to a tie. Such an arrangement is safer than the ordinary spiked rail, and the rail may be more readily removed or replaced.

Where a curved rail is employed, the clamp 9 is also preferably curved to conform to the rail, as shown in Fig. 1.

The efficiency of the clamp described de-

pends on the wedge plate being driven tightly into position and staying there. For the sake of convenience, however, it is desirable that the wedge plate be capable of removal for the purpose of removing the rail or otherwise repairing the track. I therefore provide the removably locking or retaining means hereinafter described for holding the wedge plate 10 in the position 10 to which it is driven.

As shown in Fig. 2, the small end of the wedge plate is provided with a series of holes 12 passing therethrough. These holes are preferably close together, and are equidistant. The fastening or retaining device comprises a small plate 13 having a depending pin 14 secured thereto, the pin being adapted to be passed through the opening 12 most nearly adjacent the edge of the 20 tie and engages said edge. A cross pin 15 is then passed through the projecting lower portion of the pin 14 to prevent it from being accidentally removed. The plate 13 is also preferably provided with a second depending pin 16 rigidly secured thereto but which has a looped portion 17 formed above the plate to form a lifting means for the plate. The depending pin 16 is relatively short and does not pass entirely 30 through the wedge plate although it does engage in the openings 12. The purpose of this pin is to maintain the cover plate 13 in suitable position to prevent the holes 12 from becoming filled by dirt and foreign matter collecting therein.

In use, the wedge plate 10 is driven into clamping position as far as possible. The pin 14 is then driven into that one of the holes 12 which brings it into contact with 40 the edge of the tie 5. At the same time, pin 16 enters one of the other holes to secure the cover plate 13 in position. After the pin 14 is in place, cross pin 15 is inserted to prevent the pin 14 and the cover 45 plate being accidentally removed.

In the modified construction shown in Figs. 7, 8 and 9, the wedge plate 10 is slotted at its small end, the slot being indicated at 20. Over a portion of the slot 50 is a housing 21, the parallel sides of which are provided with a series of openings 22. The fastening or retaining device comprises a body 23 adapted to slide in the slot 20, and the upper portion thereof projects above 55 the surface of the plate 10 into the housing 21. A series of holes 24 adapted to be brought into alignment with the holes 22 in the housing are provided in the fastener. At the rear of the body 23 is a depending 60 lug 25 for engagement with the edge of the tie 5.

When in use, the wedge plate 10 is driven to clamping position, as usual, after which, the fastening member 23 is placed in position 65 so that lug 25 engages the edge of the

tie and cotter pin 26 is then passed through that opening in the housing which is in alignment with one of the openings 24 in the fastener, the end of the cotter pin projecting at the other side of the housing. 70 This end is then bent to secure the pin in position in a manner well understood. The slope or curvature of the sides of slot 20, and the body 23 is such as to prevent any pivotal movement of the body relatively to 75 the wedge plate.

With the use of my invention, the wedge plates may be easily secured in position against accidental removal, but can be easily and quickly released when necessary. It 80 will also be seen that the plates may be locked in substantially the position to which they are driven, notwithstanding that some of the plates may be driven in farther than others. In other words, the locking means 85 is adjustable to variations in the positions of the plates to which they are applied. The invention is particularly useful in connection with a curved rail where the spring of the rail tends to force the clamping plate 90 loose. Transverse projections 5^a may be formed on the bottom of the tie to prevent it from slipping and portions of its surface could be roughened or corrugated as indicated at 5^b. 95

I claim as my invention:

1. The combination with a rail, of a tie, and means for securing the rail to the tie, said means including a rail engaging clamp, a wedge plate coöperating with means on 100 the tie for holding the clamp in position, means removably carried by said wedge plate for engaging one edge of the tie to hold said wedge plate against removal, and other means on said removable means for 105 preventing the accidental removal thereof.

2. The combination with a rail, of a tie, and means for securing the rail to the tie, said means including a rail clamp a wedge plate engaging the clamp and coöperating 110 with means on the tie for holding the clamp in position, means comprising a body member having a depending projection thereon for engagement with the tie, said body member being detachably carried by said wedge 115 plate, and a pin connecting the body member with the wedge plate.

3. The combination with a rail, of a tie, and means for securing the rail to the tie, said means including a rail clamp, a wedge 120 plate engaging the clamp and coöperating with means on the tie for holding the clamp in position, means comprising a body member having a depending projection thereon for engagement with the tie, said body member being adjustably carried by said wedge plate, and a pin connecting the body member with the wedge plate to hold it in adjusted position. 125

4. The combination with a rail, of a tie, 130

and means for securing the rail to the tie including a rail clamp, a wedge plate engaging the clamp and coöperating with means on the tie for holding the clamp in position, said wedge plate being provided with openings therein, and means including a body having a projection for engaging the edge of the tie through some one of the desired openings and means on the body connected to said wedge plate through some one of the other openings, said projection on the body preventing the removal of the wedge plate through its engagement with the edge of the tie.

15 5. The combination with a rail, of a tie, and means for securing the rail to the tie, said means including a rail clamp, a wedge plate engaging the clamp and coöperating with means on the tie for holding the clamp in position, said wedge plate being provided with a series of openings therein, and wedge retaining means supported on the wedge plate and comprising a body portion having a depending pin thereon projecting through any desired one of said openings, said pin

being adapted to engage the tie, and other means for preventing the accidental removal of said wedge retaining means.

6. The combination with a rail, of a tie, and means for securing the rail to the tie, 30 said means including a rail clamp, a wedge plate engaging the clamp and coöperating with means on the tie for holding the clamp in position, said wedge plate being provided with a series of openings therein, and wedge 35 retaining means supported on the wedge plate and comprising a body portion having a depending pin thereon projecting through any desired one of said openings, said pin being adapted to engage the tie, and means 40 on the wedge retaining means connected with means on the wedge plate for preventing the accidental removal of said wedge retaining means.

In testimony whereof I affix my signature 45
in presence of two witnesses.

JOHN J. BRANAGAN.
